UNITED STATES PATENT OFFICE

2,501,024

ROLLING MILL FEED TENSIONING DEVICE

Carl O. Bruestle, Rahway, N. J., assignor to Borg-Warner Corporation, Chicago, Ill., a corporation of Illinois

Application December 28, 1944, Serial No. 570,075

5 Claims. (Cl. 80—35)

1

In its broadest aspect the present invention relates to a rolling mill feed. Specifically the improvements embody an arrangement for forming a metal strip from a round wire into a ribbon-like weft thread or strand and to create tension on the strand during the rolling operation. The flat strand is for delivery to the weaving head of a machine which produces a woven screen. The screen contemplated herein comprises a mesh or fabric having horizontal members of louver-like form to exclude direct sunlight. While the arrangement is described herein as operating upon a metal wire, it is apparent the strand may be of any material desired.

In the present apparatus, a wire strand of relative small gauge and preferably round in cross-section is guided to forming or flattening members of the rolling mill while trained alternately over and under a plurality of eccentrically adjustable pulleys, and then advanced to the mill assembly. The forming or flattening members of the mill preferably comprise pressure rollers arranged with their peripheries in close proximity to each other, the space between the peripheries predetermining the thickness of the strip that is to provide the ribbon-like wefts of the woven screen. After being flattened in the milling assembly the ribbon-like strand, which is almost tissue thin and is extremely liable to become marred or distorted, is drawn away from the forming rollers by a take-off which comprises opposing rollers that frictionally engage the thin strip. These take-off rollers are geared together, one of said rollers constituting a driving member that is flexibly or yieldably coupled to a driving shaft thereby to maintain a desirable amount of tension upon the ribbon-like strip being withdrawn from the forming rollers.

It is one of the principal objects of this invention to simplify the construction of a feed for a rolling mill or forming assembly such as contemplated herein and to improve the efficiency, operation and dependability of such assembly.

Also it is one of the principal objects hereof to provide a rolling mill for rapidly producing a thin ribbon-like strand for a weaving machine.

Another principal object of the present invention is to provide a take-off arrangement for a rolling mill that is adapted to maintain proper tension on a thin ribbon-like strand to prevent distortion of such a strand, whereby the strand is delivered to the weaving head of a machine for producing a woven screen having ribbon-like wefts.

Additional objects, aims and advantages of the 35 strand, from which it is withdrawn by a tension-

2

invention contemplated herein will be apparent to persons skilled in the art after the construction and operation of the present arrangement is understood from the within description. It is preferred to accomplish the numerous objects of this invention and to practice the same in substantially the manner hereinafter described and as more particularly pointed out in the appended claims. Reference is now made to the accompanying drawings that form a part of this specification, wherein:

Fig. 1 is a diagrammatic plan of a forming or rolling mill arrangement showing the feed and tension devices thereon;

15 Fig. 1A is a perspective view of a piece of woven screen produced on the weaving machine on which the improvements are installed;

Fig. 2 is an enlarged plan of the left-hand portion of the structure disclosed in Fig. 1, comprising the guiding and pre-shaping devices;

20 Fig. 3 is a longitudinal side elevation of the structure shown in Fig. 2;

Fig. 4 is a vertical transverse section, of the pre-shaping assembly, taken along the plane of line 4—4 on Fig. 3;

25 Fig. 5 is a vertical longitudinal section along the plane of line 5—5 on Fig. 2, and also on the plane of line 5—5 on Fig. 6, and drawn to an enlarged scale;

30 Fig. 6 is a horizontal section, along the plane of line 6—6 on Fig. 5 and looking down;

Fig. 7 is a vertical axial section of the flattener assembly, the view taken along the plane of line 7—7 on Fig. 5; and

35 Fig. 8 is an enlarged vertical section of the take-off devices, the view being taken along the plane of line 8—8 on Fig. 5 and enlarged.

The drawings are to be understood as being more or less of a schematic character for the purpose of disclosing a typical or preferred embodiment of the improvements contemplated herein, and in these drawings like reference characters identify the same parts in the different views.

Referring first to Fig. 1 it will be seen the 45 strand A comprising the weft of the woven screen is received from the spool by a grooved pulley 10, then is trained successively over and under a plurality of grooved tension pulleys 12 having eccentrically arranged trunnions 13 and then passes 50 through a tapered guide tube 14 (Figs. 2 and 3) which is close to and directs the strand to the pre-shaping assembly 16. The pre-shaped weft strand A then passes through a flattener assembly 18 that forms it into a thin ribbon-like strand, from which it is withdrawn by a tension-

ing and take-off assembly 20 for delivery to a slack table 22 having a delivery mouth 24 to discharge the flat strand A into a delivery tube 26 from which the strand is taken off and intermittently fed as the wefts of the mesh or screen being woven on the machine.

The intermittent weft feed is accomplished generally by means of rapidly rotated feeding rollers 28 having geared driving connection with each other. The spindle of one of these weft feed rollers carries a pinion 30 meshing with a segmental rack 32 which is reciprocably mounted on a pivot 34. A continuously rotatable crank 36 drives the rack 32 through the medium of a pitman rod 38 pivotally connected at its ends to the crank and rack as shown in Fig. 1 and a suitable one-way clutch device (not shown) on the spindle carrying pinion 30 is effective to drive feeding rollers 28 in one direction and prevent rotation in the opposite direction.

In the operation of the arrangement above briefly described, the tensioning and take-off assembly 20 is preferably rotated at a speed proportionately faster than the flattener assembly 18 thereby exerting a pull on the ribbon-like weft strand to prevent slack, and a friction clutch assembly 39, comprising part of the driving mechanism, yieldably tensions the pull on the strand to prevent breakage thereof.

The details of this clutch assembly 39, shown in Figs. 5 and 8, comprise a driven shaft 40 journaled in an anti-friction upper bearing 42 and a floating lower bearing 44, and a sprocket 46, loose on said shaft, is rotated by a chain 48 drivingly connected to a sprocket 50 on a driving shaft 52. This latter shaft 52 carries a worm wheel 54 meshed with a worm gear 56 on a power shaft 58 that is preferably actuated by an electric motor (not shown) or other suitable prime mover. The loose sprocket 46 rests on a stop washer 60 and is anchored to a cup shaped clutch member 62, the flat radial inner face of the latter being opposed by the other clutch member or pressure plate 64. Friction pieces 66, interposed between the confronting faces of clutch members 62 and 64, are held in place by an annulus 68 connected by pins 70 to clutch member 62. The clutch member or pressure plate 64 has a hub 72 keyed to shaft 40 for sliding movement thereon, and a coiled spring 74 interposed between this hub and a stop collar 76 urges the pressure plate 64 yieldably toward the clutch member 62 carried by the sprocket 46. The stop collar 76 is internally threaded for adjustment longitudinally on a threaded portion 78 of shaft 40 to increase or diminish the tension of spring 74 and consequently the amount of pull exerted on the weft strand by the take-off and tensioning assembly 20.

Above the bearing 42, shaft 40 carries a roller 80 the hub of which is formed with a gear 82. Referring now to Fig. 8, gear 82 is meshed with a corresponding gear 84 on the hub of a roller 86 that yieldably opposes driving roller 80. The trunnions of roller 86 are journaled in anti-friction bearings 88 in the respective upper and lower arms 90 and 92 of a bifurcated slide 94 that is yieldably urged toward the driving roller 80. Slide 94 is carried in gibs 96 and is pressed towards roller 80 by a spring 98 seated in a recess in the slide with its outer end engaged with an abutment 100. When the ribbon-like weft strand A is being inserted between rollers 80 and 86 the slide 94 may be retracted by a suitable tool and released after the strand has been desirably posi-

tioned, the tension of spring 98 being sufficient to firmly engage the strand between said rollers. Preferably the tension of slide spring 98 is greater than the tension of clutch engaging spring 74 so that any slippage that takes place will be confined to the clutch members.

The pre-shaping assembly 16, receives the round wire from the tension pulleys 12 through tubular guide 14. This assembly, shown in detail in Figs. 2, 3 and 4, comprises a pair of opposing pre-shaper rollers 102 rotatably journaled in spaced upper and lower portions 104 and 105 of a yieldable hollow carrier 106, said upper portion being divided by a slot 110 (Fig. 4) to permit threading of the weft strand between said rollers 102. Carrier 106 is slidably mounted on guide rods 108 projecting horizontally from bosses 112 on the adjacent portion of the machine and provided with stops 114 at their outer ends. Springs 113, surrounding rods 108 between bosses 112 and carrier 106 urge said carrier yieldably in a direction opposite to the line of travel of the weft strand A to tighten out slack therein by maintaining the strand taut between the point of engagement with pre-shaper rollers 102 and the next or flattener rollers to which the strand is moving. The guide tube 14 is mounted on the carrier 106 by means of a bracket 116. In this assembly, the rollers 102 are adapted to effect a pre-shaping of the round weft strand by partly reducing its horizontal diameter through a flattening of its sides prior to being compressed into a thin ribbon-like strand by the flattener assembly 18 that is intermediate the pre-shaper 16 and the tensioning take-off 20 that draws the strand away from the flattener 18.

Details of the flattener assembly 18 are shown in Figs. 5, 6 and 7. Driving shaft 52 of this assembly is reduced at its ends for journaling in a fixed upper bearing 118 and a floating lower bearing 120, both of these bearings being of the anti-friction type. The upper bearing 118 being held in a seat 117 by a retainer plate 119 and the lower bearing 120 which is floating is held in place by a nut 121 screwed on shaft 52. Above upper bearing 118 the driving shaft 52 has a disc-like roller 122 secured to it by a pin 124 and there is a housing 126 enveloping the major portion of this roller 122 as seen in Figs. 5 and 7. The driven roller 128 which opposes roller 122 is secured to the upper portion of an idle shaft 130 having shoudered end portions that are journaled in upper and lower anti-friction bearings 132 and 134 carried in the eccentric bore of a sleeve 136. The lower bearing 134 which is floating is secured in place by a nut 133 screwed on shaft 130 and the upper bearing 132 is held on a seat 131 by a retainer plate 135. Between the bearings 132 and 134 shaft 130 is surrounded by a spacer tube 138 that is engaged at its ends with said bearings 132 and 134.

Means are provided for effecting the desirable degree of pressure between rollers 122 and 128 to compress the pre-shaped or partially flattened weft strand A into a thin ribbon-like form. For this purpose sleeve 136 is arranged for rotative adjustment in a cylindrical housing 140 having a bored transverse boss 148. Hollow blocks 142 and 144, have keyed connection as at 146 in the bore of boss 148 and have wedge faces 142a and 144a that are operable against the sleeve 136 as seen in Fig. 6. A rotatable clamp bolt 150 passes through the smooth bore of block 142 and screws into the threaded bore of block 144. The outer portion of bolt 150 beyond block 142 is enlarged

at 152 to bear against the adjacent end of block 142 when bolt 150 is rotated to draw the blocks into frictional clamping engagement with sleeve 136. This clamping arrangement is at the center of length of sleeve 136 so as to force said sleeve against the housing wall opposing the rolling pressure. By backing up bolt 150 the clamp is released and sleeve 136 may be turned by a rotatable worm 154 meshed with a worm wheel or annular teeth 156 in channel 158 on the sleeve 136. Worm gear 154 is formed on a countershaft 160 journaled in bearings 162 and 164 at the ends of a horizontal boss 166 on housing 140, and the angular outer end 168 of said countershaft receives a suitable tool to turn the countershaft. Clamp bolt 150 also has an angular outer portion 170 to permit the use of a tool for rotating said clamp bolt to tighten or loosen the sleeve or cylinder 136 in which shaft 130 is eccentrically arranged. Thus the pressure between the weft flattener rollers 122 and 128 may be adjusted to the exact degree required for producing the thin ribbon-like weft strand.

The flattener assembly 18 pulls the weft strand A through the pre-shaper devices 16 to reduce the diameter of the round wire or the like by creating flat portions on opposite sides thereof, and when this pre-shaped strand is engaged by the flattener assembly the strand is further reduced in thickness to a thin ribbon-like weft member ready for use in a weaving machine which produces a woven screen with louver-like weft arrangement. The tensioning assembly 20 provides a strand take-off, and since its rollers 80 and 86 are preferably operated at a peripheral rate of speed that is proportionately faster than the peripheral rate of speed of flattener rollers 122 and 128, the weft strand A is kept taut between these assemblies with slippage taking place in the friction clutch arrangement on the driving shaft 78 of the tensioning assembly 20.

Provision is made for heating the rollers 122 and 128 of the flattener assembly 18 to assist in the final step of preparing the ribbon-like strand. This is accomplished by means of suitable electric heating units 171 of annular shape that are carried in recesses 172 on the undersides of the housings 126 encompassing the flattener rollers 122 and 128. Binding posts 173, exterior to the housings are connected into the electric circuit that supplies the motor and other actuators with electric current. A safety device in the form of a micro-switch conventionally shown at 174 is interposed in the electric circuit to automatically cut off the current in the event of breakage of the weft strand. This switch has a protruding outwardly urged contact plunger 176 that is engaged by a switch operating arm 178 fulcrumed at one end on a pivot 180 and carrying a roller 182 at its other end that is engaged with the cam edge 184 of a bar 186 anchored to a side of the slideable carrier 106 of the pre-shaper assembly 16. The pull exerted by the flattener rollers 122 and 128 on the strand A is yieldably tensioned by springs 113 that normally urge the carrier 106 in a direction away from the flattener assembly. If the tension is released due to breakage of the strand, the carrier will move to the left (Fig. 2) and such movement causes the cam 184 to depress switch arm 178 thereby operating the contact plunger to break the circuit through the motor and stop the rolling mill machine.

The pre-shaper assembly 16 performs an important function in the operation of the arrangement shown in Figs. 1, 2 and 3. Due to the fact

that the wire strand A is flipped off a stationary reel or spool there is a twist in each coil leaving the reel. This would make it difficult to deliver a straight flat strand from the rolling mill assembly 18. By pre-flattening the strand before it reaches the rollers 122 and 128 of the mill this condition is overcome.

One of the rollers 102 is mounted on the eccentric portion 103 of a stud as seen in Fig. 4, to permit its bodily adjustment with respect to the opposing roller. With the arrangement shown, wherein the pre-shaping rollers 102 are mounted in the spring loaded carrier assembly 106 there is an actual stretch of the wire prior to its engagement by the final flattening rolls 122 and 128. The spacing of the pre-shaping rollers 102 is such that the pull required to draw the wire through this spacing exceeds the elastic limit of the strand. This back pull accomplishes an increase in the life of the flattening rollers 122 and 128 in addition to assuring a straight ribbon product. It is here stated that the ribbon produced is held within $\pm .0002''$, and that this extremely close tolerance is in excess of the working clearance required for the sleeve 136 for turning in its housing 140.

While this invention has been described in detail in its present preferred form or embodiment, it will be apparent to persons skilled in the art, after understanding the improvements, that various changes and modifications may be made therein without departing from the spirit or scope thereof. It is aimed in the appended claims to cover all such changes and modifications.

I claim:

1. A rolling mill for producing a ribbon-like strand from a round strand comprising opposed idle shaping rollers for exerting initial compression on opposite portions of the round strand; a reciprocable carrier supporting said rollers; yieldable means urging said carrier in a direction opposite to the line of travel of the strand past said shaping rollers; opposed flattener rollers acting on the strand to produce a ribbon-like strand, said flattener rollers being effective to pull the strand from said shaping rollers against the tension of the yieldable carrier thereby to rotatably drive said idle shaping rollers; and a tensioning take-off assembly including opposed rotatable strand engaging members beyond said flattener rollers; shafts carrying said strand engaging members, one of said shafts constituting a driving shaft; and means for effecting a driving connection between said shaft and said flattener rollers adapted to rotate said members at a peripheral speed faster than the peripheral speed of said flattener rollers, said driving connection means including friction devices adapted to provide slippage that is effective to maintain a constant tension on the strand.
2. A rolling mill for producing a ribbon-like strand from a round strand comprising opposed idle shaping rollers for exerting initial compression on opposite portions of the round strand; a reciprocable carrier supporting said rollers; yieldable means urging said carrier in a direction opposite to the line of travel of the strand past said shaping rollers; opposed flattener rollers acting on the strand to further reduce it to ribbon-like dimensions, said flattener rollers being effective to pull the strand from said shaping rollers thereby to rotatably drive said idle shaping rollers; means for effecting adjustable relative movement between said flattener rollers for predetermining the thickness of the ribbon-like strand produced

by said rollers; and a tensioning take-off assembly including opposed rotatable strand engaging members beyond said flattener rollers; a driving shaft carrying one of said strand engaging members; a driving shaft carrying one of said flattener rollers; and means for effecting a driving connection between said shafts to rotate said members at a peripheral speed faster than the peripheral speed of said flattener rollers, said driving connection means including friction devices 10 adapted to provide slippage that is effective to maintain a constant tension on the strand between said flattener rollers and the strand engaging members of the take-off assembly.

3. A rolling mill for producing a ribbon-like strand from a round strand of highly ductile metal which is unwound from a coil on a supply roll, comprising pre-shaping means defined by opposed idle shaping rolls arranged to straighten the coil and partially flatten opposite portions of the straightened round strand; a reciprocable carrier supporting said idle rollers; yieldable means urging said carrier in a direction opposed to the line of travel of the strand past said shaping rollers; in combination with opposed flattener rollers acting on the partially flattened strand to produce a thin ribbon-like strand, one of said flattener rollers being an idle roller, said flattener rollers being effective to pull the strand from said shaping rollers thereby to drive said idle shaping rollers; an idle shaft carrying said idle flattener roller; eccentrically arranged means journaling said idler shaft, said means being rotatively adjustable for predetermining the spacing of said flattener rollers and thereby the thickness of the ribbon-like strand; electromotive means driving one of said flattener rollers; circuit make and break means controlled by movement of said carrier out of normal position to break the circuit to said electromotive means; a tensioning takeoff assembly including rotatable strand-engaging members beyond said flattener rollers; and frictional clutch means providing a driving connection between said rotatable strand-engaging members and said driven flattener roller, said clutch means rotating said strand-engaging members at a faster peripheral speed than said flattening rollers for maintaining a taut pull on the strand moving away from said flattener rollers.

4. A rolling mill for producing a ribbon-like strand from a round strand of highly ductile metal which is unwound from a coil on a supply roll, comprising pre-shaping means defined by opposed idle shaping rollers arranged to straighten the coil and partially flatten opposite portions of the straightened round strand; and a reciprocable spring-packed carrier supporting said idle rollers, said carrier normally urged in a direction opposed to the line of travel of the strand past said shaping rollers; in combination with opposed flattener rollers acting on the partially flattened strand to produce a thin ribbon-like strand, one of said flattener rollers being an idle roller, said flattener rollers being effective to pull the strand from said shaping rollers thereby to drive said idle shaping rollers; housing means enclosing said flattener rollers; heating means in said housing means close to said flattener rollers; an idle shaft carrying said idle flattener roller; an eccentrically bored sleeve journaling said idler shaft; means for rotating said sleeve to bodily move said idle flattener roller with respect to its opposed roller for predetermining

the spacing of said flattener rollers and thereby the thickness of the ribbon-like strand; a prime mover driving one of said flattener rollers; control means responsive to movement of said carrier out of its normal position to effect stoppage of the prime mover; a tensioning take-off assembly including rotatable strand-engaging members beyond said flattener rollers; and frictional clutch means providing a driving connection between said rotatable members and said driven flattener roller, said clutch means rotating said strand-engaging members at a faster peripheral speed than said flattening rollers for maintaining a taut pull on the strand moving away from said flattener rollers.

5. A rolling mill for producing a ribbon-like strand from a round strand of highly ductile metal which is unwound from a coil on a supply roll, comprising pre-shaping means defined by opposed idle shaping rolls arranged to straighten the coil and partially flatten opposite portions of the straightened round strand; a reciprocable carrier supporting said idle rollers; and yieldable means urging said carrier in a direction opposed to the line of travel of the strand past said shaping rollers; in combination with opposed flattener rollers acting on the partially flattened strand to produce a thin ribbon-like strand, one of said flattener rollers being an idle roller, said flattener rollers being effective to pull the strand from said shaping rollers thereby to drive said idle shaping rollers; means for heating said flattener rollers; an idle shaft carrying said idle flattener roller; an eccentrically bored sleeve journaling said idler shaft; means for rotating said sleeve to bodily move said idle flattener roller with respect to its opposed roller for predetermining the spacing of said flattener rollers and thereby the thickness of the ribbon-like strand; electromotive means driving one of said flattener rollers; a switch in the circuit to said electromotive means, said switch being held closed by said carrier in normal position and being opened to stop said electromotive means upon movement of said carrier out of its normal position; a tensioning takeoff assembly including rotatable strand-engaging members beyond said flattener rollers; and frictional clutch means providing a driving connection between said rotatable members and said driven flattener roller, said clutch means rotating said strand-engaging members at a faster peripheral speed than said flattening rollers for maintaining a taut pull on the strand moving from said flattener rollers.
